US00D990324S

(12) **United States Design Patent** (10) **Patent No.:** **US D990,324 S**
Denison et al. (45) **Date of Patent:** **** Jun. 27, 2023**

(54) **CONTAINER**(71) Applicant: **Kraft Foods Group Brands LLC**,
Chicago, IL (US)(72) Inventors: **Joseph C. Denison**, Chicago, IL (US);
Stephen Patrick Kennedy Dow,
Willowbrook, IL (US); **Timothy Leo**
Ridley, Sleepy Hollow, IL (US)(73) Assignee: **Kraft Foods Group Brands LLC**,
Chicago, IL (US)(***) Term: **15 Years**(21) Appl. No.: **29/768,564**(22) Filed: **Jan. 29, 2021****Related U.S. Application Data**(62) Division of application No. 29/683,490, filed on Mar.
13, 2019, now Pat. No. Des. 910,435.(51) **LOC (14) Cl.** **09-03**
(52) **U.S. Cl.**USPC ..... **D9/425**(58) **Field of Classification Search**USPC D7/601, 602; D9/420, 425–429, 430,

(Continued)

Primary Examiner — Janice Patyk*(74) Attorney, Agent, or Firm* — Fitch, Even, Tabin &
Flannery LLP(57) **CLAIM**We claim the ornamental design for a container, as shown
and described.**DESCRIPTION**FIG. 1 is a perspective view of a container, showing our new
design.

FIG. 2 is a top plan view thereof.

FIG. 3 is a front view thereof, the rear view being identical.

FIG. 4 is a left side view thereof, the right side view being
identical; and,

FIG. 5 is a bottom plan view thereof.

The broken lines in the figures illustrate portions of the
design that form no part of the claimed design.**1 Claim, 3 Drawing Sheets**| (56)	References Cited
